UNITED STATES PATENT OFFICE.

EPPA H. RYON, OF WORCESTER, MASSACHUSETTS, ASSIGNOR TO CROMPTON & KNOWLES
LOOM WORKS, A CORPORATION OF MASSACHUSETTS.

LOOM MULTIPLIER MECHANISM.

No. 884,862.

Specification of Letters Patent.

Patented April 14, 1908.

Application filed December 18, 1905. Serial No. 292,145.

To all whom it may concern:

Be it known that I, EPPA H. RYON, a citizen of the United States, residing at Worcester, in the county of Worcester and State 5 of Massachusetts, have invented certain new and useful Improvements in Loom Multiplier Mechanism, of which the following is a specification.

My invention relates to a loom multiplier mechanism, by means of which certain bars of 10 the shuttle box pattern chain may be repeated, without making successive similar bars.

The object of my invention is to make an improved multiplier mechanism for looms, 15 in which a rotary and longitudinally moving cylinder or drum, having pins, or pattern indicating surfaces thereon, is used.

My invention consists in certain novel features of construction of my improvements, 20 as will be hereinafter fully described.

I have only shown in the drawings detached portions of the head motion of a loom of the well known Knowles type, shown and described in Reissue Letters Patent, No. 25 7,784, and of the shuttle box pattern chain and operating mechanism, with my improvements combined therewith, sufficient to enable those skilled in the art to understand the construction and operation thereof.

30 Referring to the drawings:—Figure 1 is a front view of a part of a head motion, and of my multiplier mechanism combined therewith, looking in the direction of arrow *a*, Fig. 4. Fig. 2 shows a different position of 35 some of the parts shown at the left in Fig. 1. Fig. 3 is a detached sectional detail of the reversing worm, shown in Figs. 1 and 2. Fig. 4 is a sectional end view of the parts shown in Fig. 1, on line 4, 4, same figure, looking in the direction of arrow *b*. Fig. 5 is a section, 40 on line 5, 5, Fig. 1, looking in the direction of arrow *b*, same figure. Fig. 6 is a section, on line 6, 6, Fig. 7, looking in the direction of arrow *c*, same figure, showing the shuttle box 45 pattern chain cylinder, and chain. Fig. 7 is a rear view of the multiplier mechanism, looking in the direction of arrow *d*, Fig. 4. Fig. 8 shows some of the parts shown at the left in Fig. 7, in a different position. Fig. 9 50 is a section, on line 9, 9, Fig. 4, looking in the direction of arrow *d*, same figure, and, Fig. 10 shows a modified construction of the two pin wheels shown in Figs. 7, and 8, detached, said pin wheels being fast on a sleeve.

55 In the accompanying drawings, 1 is a por-

tion of the head frame, 2 the upper cylinder gear, 3 the lower cylinder gear, 4 a pinion on the lower cylinder gear shaft 5, which meshes with a gear 6, to drive said gear, fast on the pattern chain cylinder shaft 7. The pattern chain cylinder shaft 7 has fast thereon a harness pattern chain barrel or cylinder 8, partially shown in Fig. 6, and also has loosely mounted thereon, a shuttle box pattern chain barrel or cylinder 9, carrying the pattern chain 10, of any ordinary construction, and in this instance consisting of rolls and tubes, mounted on bars in the usual way, see Fig. 6.

All of the above parts are of the usual and well known construction.

I will now describe my improvements.

The box pattern chain cylinder 9 is rotated independently of the pattern chain cylinder shaft 7, in this instance by a star wheel 11 connected with said pattern chain cylinder 9, and two pin wheels 12, and 13, located on opposite sides of the axis of the star wheel 11, and in this instance fast on a rotary and longitudinally moving shaft 14, mounted in suitable bearings 15' on brackets 80 or supports 15, secured to or forming a part of the loom frame, see Fig. 7.

The engagement of one of the pin wheels, as 12, with the star wheel 11, will rotate said star wheel and the box pattern chain cylinder 9, in one direction, and the engagement of the other pin wheel, as 13, with the star wheel 11, will rotate the star wheel 11, and the pattern chain cylinder 9, in the opposite direction. In case neither of the pin wheels 85 12 or 13 is engaged with the star wheel 11, as shown in Fig. 8, the star wheel 11 and the box pattern chain cylinder 9 will remain at rest, and the star wheel will be held by the inner end of the hubs 12' and 13" respectively 90 of the pin wheels 12 and 13, extending into the recessed portions of the star wheel 11, see Fig. 8.

The shaft 14, having in this instance fast thereon the pin wheels 12 and 13, has a 100 rotary movement communicated thereto through the bevel gear 16, mounted on said shaft between two of the bearings 15', and connected therewith to rotate said shaft, and to allow the shaft to move longitudinally within the hub of said gear, by a key 17, fast in the gear 16, and extending into a longitudinal slot in the shaft 14, see Fig. 8. The bevel gear 16 meshes with and is driven by a bevel gear 18, fast on a rotary shaft 19, see 110

Figs. 4, 5, and 9, which shaft extends transversely through the head, and is mounted in suitable bearings. On the opposite end of the shaft 19, at the front of the head motion, 5 is fast a pinion 20, see Figs. 1, and 5, having peripheral teeth 20' thereon, which engage with the teeth on the gear 6, and is driven by said gear. The pinion 20 has also thereon the bevel teeth 20'', see Figs. 1, and 5, to 10 be hereinafter described. The longitudinal movement of the shaft 14, carrying the pin wheels 12 and 13, to cause the box pattern chain cylinder 9 to turn in one direction or the other, or to remain at rest, is controlled 15 by the multiplier pattern cylinder or drum as follows:

The pin wheel 13 has an annular groove 13' therein, into which extends a pin on the lower end of a lever 21, pivotally mounted at 20 its upper end on a stud 21' on the frame 1, see Figs. 7 and 8. The swinging lever 21 has an elongated opening 21'' therein, to receive a stud 22' on one end of a rod 22, the other end of the rod 22 is connected with a 25 lever 23 fast on a rock shaft 24, mounted in suitable bearings on the frame, and having adjustably attached thereto the hub 25' of the pattern indicating finger or lever 25, see Figs. 4, and 9. The indicating finger 25 extends over the multiplier pattern cylinder 26, 30 to be engaged by a long pattern pin 26' thereon, or a short pattern pin 26'' thereon, or to extend into a space between said pins, and not be engaged by any pin. In this 35 way three positions of the indicating finger or lever 25 is obtained. A spring 22'', in this instance a tension spring, attached at one end to a stationary part of the frame, and at its other end to the upper end of the lever 23, 40 acts to draw inwardly said lever, and to rock the shaft 24, and move down the finger 25.

The multiplier pattern cylinder 26 has rows of holes therein, at equal distances apart, and furnished in this instance with a 45 screw thread, to receive the threaded ends of the pattern pins, which are arranged according to the desired repeat of the pattern being woven. In the present instance, the multiplier pattern cylinder 26 has twenty 50 rows of holes 26^a around its circumference, and each row has sixteen holes therein. The cylinder may be made longer or shorter as desired. The rows of holes in the direction of the length of the pattern cylinder 26 are 55 parallel to each other, but each row of longitudinal holes is located at unequal distances from the ends of the cylinder, that is the holes extend helically around the cylinder.

The pattern cylinder 26 has one end, shown 60 at the left in Fig. 5, with a square hole therein, to fit onto the square portion 27' of the shaft 27, which extends transversely through the head and is mounted in suitable bearings thereon. The opposite end of the pattern 65 cylinder 26 has a threaded hole therein,

adapted to receive and engage a worm or threaded sleeve 28. The threaded sleeve or worm 28 is loosely mounted on the rounded part of the shaft 27, and has a longitudinal movement on said shaft, but is prevented 70 from turning with said shaft, in this instance by a projection 29' on the bearings 29, extending into a notch or recess 28' in the end of the worm 28, see Figs. 4, and 5. The worm 28 has a double thread thereon with a lead 75 corresponding to the circumferential rows of holes 26^a in the cylinder 26, and mechanism is provided, or an arrangement is made so that as the cylinder 26 is revolved around the worm 28, the indicating finger 25 will 80 follow one row of circumferential holes in the cylinder 26 when it revolves in one direction, and will follow the contiguous circumferential row of holes when it is revolved in the opposite direction.

When the shaft 27 rotates in one or the other direction, through driving mechanism to be hereinafter described, the multiplier pattern cylinder 26 rotates with it, and moves longitudinally in one direction or the other, 90 according to the direction of rotation of the cylinder 26 in engagement with the worm 28, and the pattern pin 26' moving under the indicating finger 25 raises said finger, and through shaft 24, lever 23, rod 22, and lever 21, in this instance moves the pin wheel 12 into engagement with the star wheel 11, to rotate the pattern chain cylinder 9 in one direction. The pattern pin 26'' moving under the finger 25 raises said finger, and through shaft 24, lever 23, rod 22, and lever 21 moves the pin wheels, 12 and 13, both out of engagement with the star wheel 14, as shown in Fig. 8, leaving the pattern chain cylinder 9 at rest. In case no pattern pin 105 comes under the finger 25, then, through the action of the spring 22'', the finger 25 is lowered, and through shaft 24, lever 23, rod 22, and lever 21, the pin wheel 13 is moved into engagement with the star wheel 14, and the 110 pattern chain cylinder 9 is rotated in the opposite direction.

The longest pattern pin 26'', in this instance shown as the last pin on the right hand end of the multiplier pattern cylinder 115 26, see Fig. 5, and by broken lines in Fig. 9, is adapted to move under a finger or lever 30, extending over the pattern cylinder, and fast on one end of the long hub or sleeve 30', loosely mounted on the shaft 24, see Fig. 4. 120 On the other end of the sleeve 30' is fast a second finger or arm 30^a, see Fig. 4.

When the longest pin 26'' comes under the engaging end of the finger or lever 30, said lever is raised up, and the sleeve 30' rocked, 125 and through an arm 30'' on said sleeve, which has an opening therein to receive a pin 31' on an arm 31 fast on a rotary shaft 32, see Figs. 4, and 9, said shaft 32 is rocked. On the shaft 32, which is mounted in suitable 130

bearings, is fast the hub 33' of a forked arm 33, the forked end of which engages with an annular groove 34' in the hub of a pin wheel 34, see Fig. 1, to move said pin wheel, splined 5 on the shaft 35, which is mounted in suitable bearings, into engagement with a star wheel 36 loosely mounted on a stud 37, supported in a bracket 38. A spring 33'' coiled around the hub 33' of the arm 33, and bearing at one 10 end against the inside of said arm, and at its other end against a stationary part, acts to move outwardly the arm 33, and disengage the pin wheel 34 from the star wheel 36.

The star wheel 36 has a hub 36' on one side 15 thereof, with a cam groove 36'' therein, to receive a pin on the upper end of a swinging lever 39, which lever is pivotally mounted at its lower end on a stud 40. The lever 39 is connected by a link 41 with one arm of an 20 angle lever 42. The other arm of the angle lever 42 is adjustably connected with the upper end of a link 43, the lower end of which is pivotally connected with one arm of an angle lever 44, pivotally mounted on a stud 25 45, see Fig. 5. The other arm of the angle lever 44 carries a pin 44', which extends into an annular groove 28'' at the end of the threaded sleeve or worm 28, see Fig. 5.

The shaft 35 has a rotary motion communicated thereto, from the bevel teeth 20'' on 30 the pinion 20, which mesh with the bevel gear 46 fast on the inner end of the shaft 35, see Fig. 1. On the shaft 35 is in this instance a segment or detached portion 47 of a worm, 35 having a straight tooth or dwell portion, and secured to the shaft 35, in this instance by screws 47', see Fig. 3. Loosely mounted on the shaft 35, and adapted to move longitudinally thereon, is a sleeve 48, having thereon 40 two worm toothed portions 48', a right and left, and each one adapted to be moved into line with the worm portion 47, fast on the shaft 35, to form one complete worm thread, either a right or left hand thread. The 45 sleeve 48 has in this instance at one end, an annular groove 48'' therein, to receive the yoke shaped lower end of one arm of the angle lever 42. On the front end of the multiplier pattern cylinder shaft 27 is fast a worm gear 50 49, which is adapted to be engaged by and rotated through the rotation of the reverse worm 48, in one direction or the other, according to the position of the reverse worm 48, see Figs. 1, and 2. The worm or sleeve 55 48, loose on the shaft 35, in connection with the segment 47 fast on said shaft, acts as a reversing worm, to rotate the pattern cylinder shaft 27 in either direction, and through the rotation of said shaft, to rotate the pattern cylinder 26, in either direction.

The movement of the lever 42, through link 41 and lever 39, moved by the rotation of the star wheel 36 having the cam groove hub 36', will move the reversing worm sleeve 60 48 longitudinally on the shaft 35, into the

position shown in Fig. 1, to cause the worm gear 49 to rotate in one direction, or into the position shown in Fig. 2, to cause the worm gear 49 to rotate in the opposite direction. The rotation of the worm gear 49 rotates the 70 shaft 27 and with it the pattern cylinder 26. The movement of the lever 42, through link 43 and angle lever 44, will move the worm sleeve 28 longitudinally on the shaft 27 and with it the pattern cylinder 26, to bring a 75 different series of holes and pattern pins under the indicating finger 25.

When in the revolution of the pattern cylinder 26 the longest pattern pin 26''' comes under the indicating finger 30, then 80 said finger is raised and the sleeve 30' rocked, and through the arm 30'', the shaft 32 is rocked, and the forked arm 33 moved to cause the pin wheel 34 splined on the rotary shaft 35, to move into engagement with 85 and rotate the star wheel 36. The rotation of the star wheel 36, through the cam groove 36' in the hub thereof, and the swinging lever 39, link 41, and angle lever 42, cause the reversing worm 47 to be moved in one direction 90 or the other; and at the same time, through link 43 and angle lever 44, the worm 28 will be moved longitudinally on the shaft 27, and cause the cylinder 26 to be moved longitudinally.

In Fig. 10 is shown a modified construction of the pin wheels 12 and 13. In said figure, the pin wheels 12 and 13 are shown fast on each end of a sleeve 14^a, which sleeve may be loosely supported on the shaft 14 and 95 have a longitudinal movement thereon, instead of the shaft 14 having a longitudinal movement, as above described.

It will be understood that the details of construction of my improvements may be 100 varied if desired, and they may be adapted to be applied to different forms of box pattern chain mechanisms.

The driving mechanism particularly shown in Figs. 1, 2, and 3 is not claimed herein, as 110 the same forms the subject-matter of another application, a division of this application.

Having thus described my invention, what I claim as new and desire to secure by Letters Patent is:—

1. In a multiplier mechanism, a multiplier cylinder having two rows of pattern surfaces arranged in parallel helical curves around the periphery thereof, an arm adapted to bear against said pattern surfaces, means to rotate said cylinder, and means to shift said cylinder longitudinally to change the operating rows of pattern surfaces relative to said arm. 120

2. In a loom pattern mechanism, a multiplier mechanism, a pattern chain cylinder, 125 a wheel connected therewith, and means controlled by the multiplier mechanism, to rotate said wheel in a forward or backward direction a predetermined number of picks or cause it to remain in a locked position. 130

3. In a loom pattern mechanism, a pattern chain cylinder, a multiplier mechanism, means operative to rotate said cylinder in a forward or backward direction, means to lock said cylinder in a position at rest, said locking means comprising a sliding and rotatable pin wheel controlled by said multiplier mechanism. 40
4. In a loom pattern mechanism, a pattern chain cylinder, a multiplier mechanism, means operative to rotate said cylinder in a forward or backward direction, and means to lock said cylinder in a position of rest, said means consisting of a sliding and a rotatable 45 double pin wheel controlled by said multiplier mechanism. 50
5. In a loom pattern mechanism, a rotatable cylinder, a plurality of pattern surfaces on the periphery thereof, a support for one end of said cylinder having a screw-thread thereon, a rotatable shaft extending through said cylinder, connection between said shaft and said cylinder, and means to impart to said shaft a step by step rotation. 55
6. In a loom pattern mechanism, a multiplier pattern cylinder, a worm-wheel connected therewith, a worm having a dwell thread portion, and a right and a left hand thread portion, and means to slide said right and left hand thread portion, to bring either the right or left hand thread into engagement with the teeth of said worm-gear to turn the same. 60
7. In a loom pattern mechanism, a pattern cylinder, a worm gear connected therewith, a worm having a dwell thread portion, and a right and a left hand thread portion, and means to rotate said worm, and means to bring either the right or left hand thread portions into alinement with the dwell thread 65 portion. 70
8. In a loom pattern mechanism, the combination with a pattern chain cylinder, of a star wheel, a pin wheel having two pin portions and a locking portion thereon, to be moved to bring either pin portion into engagement with said star wheel, or both pin portions out of engagement with said star wheel, and the locking portion into engagement with said star wheel. 75
9. In a loom pattern mechanism, the combination with a pattern chain cylinder, of a star wheel, a pin wheel having two pin portions, and a locking portion thereon, to be moved to bring either pin portion in the path of said star wheel, or both pin portions out of the path of said star wheel, a multiplier mechanism, and means controlled by said multiplier mechanism to move said pin wheel longitudinally. 80
10. In a loom pattern mechanism, a pattern cylinder having pattern surfaces thereon, and means to drive said cylinder, one or more of said pattern surfaces adapted to engage a lever, and said lever, a cam and driving mechanism therefor, and connections from said lever to the driving mechanism of said cam, and connections from said cam, to the driving mechanism of said cylinder, and to the mechanism for moving said cylinder longitudinally and said last mentioned mechanism. 85
